UNITED STATES PATENT OFFICE.

THEODORE H. WINCHESTER, OF BALTIMORE, MARYLAND, ASSIGNOR TO
CHARLES J. CARY, OF SAME PLACE.

DESIGN FOR TYPE.

SPECIFICATION forming part of Design No. 14,403, dated November 6, 1883:

Application filed April 30, 1883. Term of patent 3½ years.

To all whom it may concern:

Be it known that I, THEODORE H. WINCHESTER, a citizen of the United States, residing at Baltimore, in the State of Maryland, have invented a certain new and original Design for Type, of which the following is a specification, reference being had therein to the accompanying drawing.

The nature of my design is clearly shown in 10 the accompanying typographic impression, which serves as a drawing; and it consists of capitals, lower-case, figures, and points. In general, the body of the letter or character is of quadrilateral form, with angles oppositely 15 placed in a direction from left to right, and the angles are unequal. Take, for instance, the capital letter C. Here are three angles—the upper, the lower, and the one at the side. The upper and lower ones are less than the one 20 at the side. The sides of the parts which form

the body may be of equal or unequal length; but where in one letter there are several angles, they are not equal—that is, there is a variance between the upper or lower angles and those at the sides. Some of the angles are obtuse and some acute. 25

What I claim, and desire to secure by Letters Patent, is—

The design for printing-type herein shown and described, consisting of the bodies having 30 quadrilateral form, with angles oppositely placed in a direction from left to right, and a variance between the upper or lower and the side angles.

In testimony whereof I affix my signature in 35 presence of two witnesses.

THEODORE H. WINCHESTER.

Witnesses:

J. EDWARD MORRIS,
JNO. T. MADDOX.
